Primary Examiner—B. J. Bullock*Attorney, Agent, or Firm*—Antonelli, Terry, Stout & Kraus**[57] CLAIM**

The ornamental design for a draw-operated lock handle, as shown and described.

DESCRIPTION

FIG. 1 is a perspective view of the draw-operated lock handle in a locked position;

FIG. 2 is a side view of the draw-operated lock handle in the locked position;

FIG. 3 is a front view of the draw-operated lock handle; and,
FIG. 4 is a perspective view of the draw-operated lock handle in an unlocked position.

The broken lines in FIGS. 1-4 showing a portion of a panel on which the draw-operated lock handle and a lock operated by the draw-operated lock handle are mounted and a housing of the lock are for illustrative purposes only and form no part of the claimed design.
